UNITED STATES PATENT OFFICE.

JACOB SCHRAM AND LOUIS SCHRAM, OF CHICAGO, ILLINOIS.

MOLDING.

SPECIFICATION forming part of Letters Patent No. 352,360, dated November 9, 1886.

Application filed September 27, 1886. Serial No. 214,599. (No model.)

To all whom it may concern:

Be it known that we, JACOB SCHRAM and LOUIS SCHRAM, citizens of the United States, residing at Chicago, in the county of Cook 5 and State of Illinois, have invented a certain new and useful Improvement in Moldings; and we hereby declare the following to be a full, clear, and exact description of the same.

Our improvement relates to the class of ornamental strips commonly formed, at least as to the body or main portion, of wood, though other materials are also employed to produce them, and used for various purposes of ornamentation, among which may be mentioned 15 decoration of rooms and the forming of decorative frames for pictures, mirrors, and the like, or ornamental boxes. It is our object to provide a construction of such strips, to which, for want of a better term, we apply the term 20 "molding," which shall afford an attractive and useful novelty.

Our invention consists, broadly, in the body portion or base having open ornamental work secured upon it over an intervening strip of 25 fabric forming the background; and it also consists in the specific construction of our improved article of manufacture.

In the drawings, Figure 1 represents a picture or mirror frame formed of our improved 30 molding. Fig. 2 shows a broken strip of molding constructed in accordance with our invention; and Fig. 3 is a transverse section of the same, illustrating the details of construction.

35 A is the body portion or base of the article, commonly formed of wood, which may be gilded, or of the more decorative kinds, which take polish.

Though we describe the materials which we 40 commonly employ for producing our new molding, we do not, of course, confine ourselves to any particular ones, as obviously various materials may be used for producing the desirable result afforded by our improved construction. Thus the part A may be metal or a 45 suitable composition. The open ornamental work B may be molded putty, colored in any desired hue, as on the specimens shown in the figures of the drawings, which are copied 50 from samples of our improvement, though it may be scroll or any other form of open ornamental work, and the interposed strip of fabric C may be cloth or paper of any suitable hue, which, being visible through the 55 open-work, produces the desired decorative

effect. We are, however, desirous of expressly confining ourselves to the employment of a suitable fabric in the position of the strip C.

We prefer to provide the body or base A 60 with a longitudinal groove or recess, r, deepened slantingly at its sides, as shown at r' in Fig. 3, and to contain the parts C and B, and form inclosing lateral edges q. The strip of fabric C—paper or cloth of the desired hue or 65 pattern—is secured by gluing it on the base of the recess r, to cover the base and form the background from which the desired effects are derived, the lateral edges being caused to enter the depressed or deepened portions r' of 70 the recess r, where they are also glued, and the ornamental or open work B is mounted on the fabric C and glued in place.

The article thus produced affords molding which may be made to suit any taste or requirement in decoration by providing the parts A, B, and C in desired relative hues. 75

What we claim as new, and desire to secure by Letters Patent, is—

1. As a new article of manufacture, molding comprising, in combination, the body portion A, fabric C, secured upon the body portion, and ornamental open-work B, secured upon the fabric, substantially as and for the purpose set forth. 80

2. As a new article of manufacture, molding comprising, in combination, the body portion A, provided with a longitudinal recess, r, a strip of fabric, C, secured in the recess r, and ornamental open-work B, secured in the recess r upon the fabric C, substantially as and for the purpose set forth. 85 90

3. As a new article of manufacture, a molding comprising, in combination, the body portion A, provided with a longitudinal recess, 95 r, to afford lateral ledges q, and lateral recesses r' within the recess r, a strip of fabric, C, secured within the recesses r and r', to form the ground, and ornamental open-work B, secured upon the fabric C, substantially as 100 and for the purpose set forth.

4. The combination of the base A, ornamental open-work B, and interposed strip of colored fabric C, substantially as and for the purpose set forth.

JACOB SCHRAM.
LOUIS SCHRAM.

In presence of—

J. W. DYRENFORTH,
GEORGE C. COOK.
